(57) **CLAIM**

The ornamental design for a miter saw, substantially as shown and described.

DESCRIPTION

This application claims priority from U.S. patent application Ser. No. 09/920,555, which was filed in Aug. 1, 2001, pending.

FIG. 1 is a right front perspective view of a miter saw showing our new design with the cutting unit in a first position;

FIG. 2 is a left front perspective view of the miter saw of FIG. 1;

FIG. 3 is a front view of the miter saw of FIG. 1;

FIG. 4 is a rear view of the miter saw of FIG. 1;

FIG. 5 is a left side view of the miter saw of FIG. 1;

FIG. 6 is a right side view of the miter saw of FIG. 1;

FIG. 7 is a top view of the miter saw of FIG. 1;

FIG. 8 is a bottom view of the miter saw of FIG. 1;

FIG. 9 is a left front perspective view of the miter saw of FIG. 1 with the cutting unit in a second position;

FIG. 10 is a right front perspective view of the miter saw of FIG. 1 with the cutting unit in a third position;

FIG. 11 is a front view of the miter saw of FIG. 1 with the cutting unit in a fourth position; and,

FIG. 12 is a front view of the miter saw of FIG. 1 with the saw in a fifth position.

The broken line showing is for illustrative purposes only and forms no part of the claimed design.
